UNITED STATES PATENT OFFICE.

JOHN EDWARD THORNTON, OF LONDON, ENGLAND.

FILM MATERIAL FOR CINEMATOGRAPH AND OTHER POSITIVE FILMS.

Original application filed December 13, 1923, Serial No. 680,511, and in Great Britain December 27, 1922.
 Divided and this application filed June 8, 1925. Serial No. 35,760.

The object of this invention is to provide a special form of ready-colored film-material for use in producing two-color positive pictures by photographic printing methods upon continuous strips of sensitive film for cinematograph pictures or for stationary pictures in series; and particularly for producing such positives of the special type described in a concurrent application Serial No. 680,511 filed 13th December 1923, in which two-color series pictures are produced as a single film of standard width and thickness, by building up from a double-width film of half standard thickness and by printing two section-images simultaneously side-by-side, but of different complementary colors such as orange-red and blue-green, from a suitable pair of negative-images or printing-clichés.

Hitherto two-color films have been produced by printing (a) two images upon opposite sides of a central celluloid or similar support sensitized upon both sides, or (b) by printing each image upon one side of a separate celluloid or similar thinner support, and then cementing the two supports back to back to form such central support, and by dyeing, toning, or otherwise coloring the two series images after printing.

This subsequent coloring operation has proved inconvenient as it involves the need for special care to ensure matched density of the separate coloring, and if such care is insufficiently exercised the film-printer suffers the loss of much expensive material.

By the present invention a far more convenient and certain process of producing the finished prints is rendered possible.

According to this invention the two colorings of exactly the correct shade are incorporated with the film-material during its manufacture in exactly the correct proportions, and all the film-printer has to do is to correctly expose and develop the sensitive film-material to a standard time and temperature in order to produce perfect prints by automatic machinery without need for the old-style methods of hand development.

Ready-colored film-material such as herein described can be used for producing prints having relief images by exposing from the back through the celluloid and developing from the front (or sensitive) face. It can also be used for producing non-relief images

by printing and developing from the front (or sensitive) face.

It also allows the construction of two-piece two-color films with their images enclosed between two thin celluloid supports which form outer covers; or with their images on the two opposite outsides, with a central celluloid support within.

By using this double-width positive-film-material with the coloring matter incorporated therein in conjunction with a double-width negative strip or printing-cliché, exposures for both sections of the same image are made simultaneously, both images are developed and treated simultaneously and expansion or contraction of both sections is uniform, so that both images are of exactly the same size when finished and dried, and when the printed film is longitudinally severed to produce two single-width strips the two parts of the same picture will accurately register when the two films are superimposed and cemented together.

Different sensitizing processes.

The film material may be sensitized by any known and suitable process; for instance, gelatino-silver-bromide, gelatino-silver-chloride; and bichromated gelatine; or in any other way.

Referring to the accompanying drawings:

Fig. 1 is a face view of a sensitized ready-colored double-width film before printing, one half colored orange-red and the other half colored blue-green.

Fig. 2 is a similar view showing the film perforated before printing.

Fig. 3 is a similar view of the film after printing with two section images of different colors before slitting into two.

Fig. 4 is a view of the completed film with the two parts superposed and cemented together either face-to-face or back-to-back.

Fig. 5 is a similar view of wide web with alternating stripes of color.

Manufacturing the film-material.

In manufacturing the film itself I start by forming a very thin transparent base A of celluloid, cellulose-acetate, or similar waterproof material. A suitable thickness is .0015 inch. This is coated upon one side

with an adhesive substratum B of the kind known to those versed in the art of film manufacture. When dry a further coating C is applied, of a thickness of about .001 5 inch, consisting of a suitable colloid such as gelatine, gum, albumen, fish glue or the like, according to the type of sensitizing process adopted, with which is incorporated either opaque pigment as used in the carbon process; or dye; or pigment and dye; or silver-bromide and pigment; or silver-bromide, dye, and a mordant; or silver-bromide, pigment, dye, and a mordant. The average 10 monochrome standard film is about .006 inch thick, whereas these section films are each less than .003 inch thick, until joined together, when they yield a completed film of the standard thickness.

The film-support may be a double-width 20 strip upon which the colored colloid is coated in the form of two differently-colored parallel stripes, but for convenience it is preferred to manufacture the film as a wide web, the colored colloid being applied as a 25 series of alternating stripes of orange-red and blue-green, each extending longitudinally of the web, and when slit into double-width strips, each strip comprises the 30 two pairs forming one set of the complementary colors required to produce complete two-color pictures.

The strips are next perforated to suit the printing and other machines by which the prints are to be produced.

35 *Characteristics of different sensitizers.*

If the film contains silver-bromide it will 40 be of the rapid printing variety, requiring a short exposure to light, subsequent developing and fixing, followed by treatment in a hardening and bleaching or oxidizing bath. Alternatively silver-chloride, iodide or other silver salts may be used.

If the film does not contain silver salts the 45 colloid will require sensitizing in a bath of a suitable bichromate salt, followed, after printing, by removal of the unchanged or unhardened colored colloid.

50 It is possible to make a number of variations in the methods of printing the film, according to methods of sensitizing adopted, and these are described in detail in a concurrent application which deals with production of the print.

55 By this invention is produced a ready-colored film-material of double-standard width and half-standard thickness, for the production of cinematograph or other two-color positives in series in the form of films 60 of standard width and standard thickness, and of the type built-up from two single-width films of only half-standard thickness, and which after printing are cemented together either face-to-face (printed-colloid to printed-colloid) or back-to-back (celluloid-

support to celluloid-support) to form a single film of standard width and thickness.

What I claim as my invention and desire to protect by Letters Patent is:—

1. A film material for the production of 70 two-color film-positives comprising a base support of transparent waterproof material double the width and half the thickness of the finished film positive, a stripe of colored colloid longitudinal of the film of one color 75 coated on one half of the base and a parallel longitudinal stripe of colored colloid of another color coated upon the other half of the base.

2. A film material for the production of 80 two-color film-positives comprising a base support of transparent waterproof material double the width and half the thickness of the finished film positive, a stripe of colored colloid longitudinal of the film of one color 85 coated on one half of the base and a parallel longitudinal stripe of colored colloid of a complementary color coated upon the other half of the base.

3. A film material for the production of 90 two-color film-positives comprising a base support of transparent waterproof material double the width and half the thickness of the finished film positive, a longitudinal stripe of colloid colored orange-red coated 95 upon one half of the base and a parallel longitudinal stripe of colloid colored blue-green coated upon the other half of the base.

4. A film material for the production of 100 two-color film-positives comprising a base support of transparent waterproof material double the width and half the thickness of the finished film positive, a strip of sensitized colored colloid longitudinal of the film of one color coated on one half of the base 105 and a parallel longitudinal stripe of sensitized colored colloid of another color coated upon the other half of the base.

5. A film material for the production of 110 two-color film-positives comprising a base support of transparent waterproof material double the width and half the thickness of the finished film positive a stripe of sensitized colored colloid longitudinal of the film of one color coated on one half of the base 115 and a parallel longitudinal stripe of sensitized colored colloid of a complementary color coated upon the other half of the base.

6. A film-material for the production of 120 two-color film-positives comprising a base support of transparent waterproof material double the width and half the thickness of the finished film positive, a longitudinal stripe of sensitized colloid colored orange-red coated upon one half of the base and a 125 parallel longitudinal stripe of sensitized colloid colored blue-green coated upon the other half of the base.

7. A film-material for the production of 130 two-color cinematograph film-positives com-

- prising in its construction a strip of transparent waterproof material of half standard thickness coated with a layer of colloid with which is incorporated coloring matter the
- 5 5. colored colloid comprising a plurality of alternating longitudinal stripes of two complementary colors adapted to be severed into strips of double standard width.
8. A film-material for the production of 10 two-color cinematograph film-positives comprising a strip of celluloid of half standard thickness, a layer of colloid coated thereon with which is incorporated coloring matter in a plurality of alternating longitudinal 15 stripes of orange-red and blue-green adapted to be severed into strips of double standard width with two stripes of color on each.
9. A film material for the production of 20 two-color cinematograph film-positives comprising in its construction a strip of transparent waterproof material of half standard thickness coated with a layer of sensitized colloid with which is incorporated coloring matter the sensitized colored colloid comprising 25 a plurality of alternating longitudinal stripes of two complementary colors adapted to be severed into strips of double standard width.
10. A film material for the production of 30 two-color cinematograph film-positives comprising a strip of celluloid of half standard thickness a layer of sensitized colloid coated thereon with which is incorporated coloring matter in a plurality of alternating longitudinal 35 stripes of orange-red and blue-green adapted to be severed into strips of double standard width with two stripes of color on each.
11. A ready-colored film-material for the 40 production of cinematograph two-color film-positives comprising in its construction and manufacture the following arrangement and combination of parts:—(A) a base-support of transparent waterproof material of double the width and half the thickness of the 45 finished film; (B) a layer of adhesive substratum superimposed upon the base-support A, and effecting a union between layers A and C; (C) a layer of colloid, spread in the 50 form of two longitudinal parallel stripes differently-colored and directly superimposed upon the substratum-layer B and indirectly superimposed upon the base-support A.
12. A ready-colored film-material for the 55 production of two-color cinematograph film positives, comprising in its construction and manufacture the following arrangement and combination of parts:—(A) a base-support of celluloid of double-standard width and 60 half-standard thickness; (B) a layer of adhesive substratum superimposed upon the base-support A, and effecting a permanent union between layers A and C; (C) a layer of colored gelatine, spread in the form of 65 two complementary-colored parallel stripes longitudinally of the film and directly superimposed upon the substratum-layer B and indirectly superimposed upon the base-support 70 A.
13. A ready-colored film-material for the 75 production of two-color cinematograph positives comprising in its construction a base support of transparent waterproof material of double-standard width and half-standard thickness, a layer of adhesive substratum superimposed on the base, a layer of colored colloid in two longitudinal parallel stripes adhered to the base by the adhesive, the colored stripes comprising orange-red coloring 80 matter incorporated with the colloid covering one half of the film and with blue-green coloring matter incorporated in the colloid covering the other half of the film the two colors being complementary to each other 85 and suitably balanced to give a true blending in a printed picture and a sensitizing medium incorporated in the colored colloid layer.
14. A ready-colored film-strip as in claim 90 1, provided with perforations for accurately registering the prints upon the double-width strip, and for moving the film through projection apparatus when the two thin films have been cemented together to form a 95 single-film-strip.

In testimony whereof I have hereunto set my hand.

JOHN EDWARD THORNTON.
